United States Patent

Des. 241,334
Patented Sept. 7, 1976

241,334

ROOF STRUCTURE

Peter Howard, New York, N.Y., assignor to Imre
Florentino Associates, Inc., New York, N.Y.

Filed Nov. 22, 1974, Ser. No. 526,386

Term of patent 14 years

Int. Cl. D25—03

U.S. Cl. D25—56

FIG.1

FIG.4

FIG. 3

FIG. 1 is a perspective view of said ornamental design for said roof structure.

FIG. 2 is a top plan view of said ornamental design for said roof structure.

FIG. 3 is a front elevational view of said ornamental design for said roof structure.

FIG. 4 is a side elevational view of said ornamental design for said roof structure.

The dotted line showing of the support tower is for illustrative purposes only and forms no part of the claimed roof structure.

I claim:

The ornamental design for a roof structure, as shown and described.
